UNITED STATES PATENT OFFICE.

JOHN E. ANDERSON, OF JAMESTOWN, NORTH DAKOTA.

PUMP.

SPECIFICATION forming part of Letters Patent No. 684,398, dated October 15, 1901.

Application filed January 4, 1901. Serial No. 42,114. (No model.)

To all whom it may concern:

Be it known that I, JOHN E. ANDERSON, a citizen of the United States, residing at Jamestown, in the county of Stutsman and State of North Dakota, have invented a new and useful Pump, of which the following is a specification.

This invention relates to pumps; and it has for its object to provide a construction where-
10 in the casing of the pump will afford a means for circulation of air, so that the well in which the pump is placed may be ventilated, al- though the top of the well is closed a further object of the invention being to provide a con-
15 struction that will permit of attachment of different styles of suction-pipes interchange- ably to suit various conditions, further ob- jects and advantages of the invention being evident from the following description.

20 In the drawings forming a portion of this specification, and in which like numerals of reference indicate similar parts in the several views, Figure 1 is a vertical section taken through the pump and showing it applied to a well and equipped with a removable pipe-
25 head having an iron suction-pipe engaged therewith. Fig. 2 is a sectional view showing the lower end of the extension of the cylinder of the pump and with a wooden pump or suction tube engaged therewith. Fig. 3 is
30 a view similar to Fig. 2 and showing a suction-pipe connected with the cylinder extension and including flanged sections. Fig. 4 is a vertical section showing a modification. Fig. 5 is a sectional detail of the upper end of the pump shown in Fig. 4.

Referring now to Figs. 1, 2, and 3 of the drawings, the present pump comprises a barrel 5 of cylindrical form and at the lower end 40 of which is an outwardly-directed flange 6, upon which rests the outwardly-flanged lower end of a casing 7 and to which said casing is bolted, as shown. The casing is separated from the barrel 5 by a continuous interspace, 45 and the upper end thereof is closed by a cap 8. A discharge-spout 9 is passed inwardly through a side of the casing and communicates with the barrel at the proper elevation, and preferably at the opposite side of the 50 casing there is disposed a water-outlet pipe

10, which connects with the barrel near its lower end to permit of drainage of water from the barrel to prevent freezing. This outlet-pipe has a valve 11, from which extends an operating-rod 12, the upper end of which is 55 journaled in a bracket 13 on the side of the pump-casing and has a terminal operating-handle, as shown. In placing the pump in a well the casing projects both below and above the cover 14, the discharge-spout and the 60 valve-operating handle lying above the cover, as shown. Openings 15 are formed through the casing just above the bottom flange thereof, and a second series of openings 16 are formed in the casing just below the cover, 65 while a third series of openings 17 are formed in the casing adjacent to the upper end thereof. The cap of the casing has a depending flange 18, which incloses the upper end of the casing and is removable therefrom, and this 70 flange is notched, so as to expose the openings 17. These several series of openings permit of a circulation of air through the casing between it and the barrel and from one side to the other of the well-cover, thus insuring 75 proper ventilation of the well. A cylindrical extension 20 is provided for the barrel and has a diameter equal to that of the barrel, and at the upper end of this extension is a flange 21, which is bolted against the under side of the 80 flange 6 to hold the pump-barrel and its extension in axial alinement. The extension 20 has an inwardly-directed shoulder 22 adjacent to its lower end and upon which rests a disk 23, having a central opening from which rises a 85 cylindrical valve-seat 24, that portion of which that receives the valve 25 lying in a plane above the disk. The valve 25 mentioned is a common form of upwardly-opening puppet-valve. In the extension 20 and above the 90 disk 23 is a plunger or piston 26, to which is connected the piston-rod 27, extending upwardly through the pump-barrel and connected at its upper end to the inner end of the handle or lever 28 of the pump, which han- 95 dle is pivoted in bearings upon the casing. The piston has perforations therein, over which is disposed an upwardly-opening flap- valve 29, although it will of course be under- 100 stood that a different specific style of valve

may be used. The cylindrical extension 20 is adapted to receive interchangeably several different styles of suction-pipes, and in Fig. 1 there is shown a common form of iron suction-pipe 30. This pipe 30 is screwed into a head 31, at the upper end of which is an outwardly-directed flange 32, disposed against the under side of a flange 33 at the lower end of the extension 20 and against which it is bolted to permit of ready removal. When it is desired to use a suction-pipe such as is shown in Fig. 3 and consisting of sections 34, having radiating flanges at their ends, such sections are connected by bolting the flange 15 of one against the flange of the next and then bolting the flange of the uppermost section against the flange 21, as illustrated.

To permit of substitution of the common form of wooden suction-pipe made up of 20 wooden tubes having one end tapered and the opposite end provided with a corresponding socket, the lower end of the extension 20 has its bore tapered inwardly from the rim of the extension to the shoulder 22, this taper 25 corresponding to the taper given the ends of the tubes. A suitable number of the wooden sections are connected in the usual manner, and the tapered end of the series of connected sections is engaged in this lower 30 end of the pump-barrel, it being understood, of course, that these different suction-tubes are for interchangeable attachment. With this construction it will be seen that there is provided a construction which insures an efficient 35 ventilation, in which freezing will be prevented, and which permits of attachment of different styles of suction-pipes.

In practice modifications of the specific construction shown may be made and any 40 suitable materials and proportions may be used for the various parts without departing from the spirit of the invention.

In Figs. 4 and 5 of the drawings there is shown a different specific embodiment of the 45 invention, wherein the casing 40 has an inwardly-directed flange 41 at its lower end which sustains a concentric tubular extension 42, extending above and below the flange, said extension having a lower flange 50 43, adapted for attachment of a head 31 or the extension 34, hereinbefore referred to. The extension 43 has shoulders 44 corresponding to the shoulders 22, upon which is disposed a valve-carrying disk 45. The barrel 55 47 in this construction is tubular and is fitted over the upper end of the extension 42 and has a flange 48 at its lower end, which is seated upon a gasket 49 upon the flange 41. To hold the barrel firmly seated on this gas- 60 ket in such manner as to prevent leakage, ears 50 are formed on the inner surface of the casing and corresponding ears 51 are formed upon the outer face of the barrel, at the upper end thereof, these ears alining in pairs and 65 having perforations therethrough with which are engaged bolts 52, which when screwed

up draw the barrel downwardly into the casing. A piston 53 is disposed in the barrel and has a rod 54, with which is connected the usual handle 55. The drain-cock 56 in the present instance has its valve-casing disposed between the pump barrel and casing, the discharge-spout being passed outwardly through the pump-casing, and the operating-rod 57 is taken upwardly between the pump-barrel and its casing and outwardly through the top of the casing, where it is provided with an operating-handle 58. The discharge-spout 60 for the pump is passed inwardly through the casing and screwed into the barrel, and it will be seen that by removing this spout and the drain-spout the barrel may be readily lifted from the casing after the top 61 has been removed and the holding-bolts have been detached. Thus when desired the pump 85 may be readily disassembled for repairing or for other purposes.

What is claimed is—

1. In a pump, the combination with a barrel, of a casing disposed to inclose the barrel 90 and separated therefrom by an interspace, said barrel and casing having each a flange disposed for one to sustain the other and the part carried thereby, a well-cover engaged with the casing between the ends of the casing, openings leading into the casing above and below the cover, and a drain-pipe connected with the barrel below the cover and having a valve provided with an actuating-rod extending above the cover. 95

2. In a pump, the combination with a barrel having a discharge, of a casing disposed to inclose the barrel and having an inwardly-directed flange at its lower end, said casing above the flange being separated from the 105 barrel by an interspace, said barrel and casing having each a flange disposed for one to sustain the other and the part carried thereby, a cylindrical extension for the barrel formed integral with the flange of the casing 110 and extending above the flange, and over which extension the barrel is disposed to rest upon the flange of the casing, said extension being provided with an upwardly-opening valve, and a piston disposed in the extension 115, said piston having an upwardly-opening valve and having means for operating it.

3. In a pump, the combination with a barrel, of a casing for the barrel having ventilating-openings disposed to lie inside and outside of a well respectively, said barrel and casing having each a flange disposed for one to sustain the other and the part carried thereby, and a cylindrical extension sustained by one of said flanges, said extension 120 having a flange at its lower end to receive the flange of a suction-pipe and having the lower end of its bore tapered to receive the tapered end of a suction-pipe interchangeably with the first-named suction-pipe. 125

4. A cylindrical extension for a pump-barrel having an internal shoulder to receive a

valve and provided with a terminal flange for attachment of a suction-pipe, the lower end of the extension having its bore tapered to receive the tapered end of a suction-pipe interchangeably with the attachment of a pipe to the flange.

In testimony that I claim the foregoing as

my own I have hereto affixed my signature in the presence of two witnesses.

JOHN E. ANDERSON.
